(57) **CLAIM**

An ornamental design for a funnel for the ejection port of a shotgun, as shown and described.

DESCRIPTION

FIG. 1 is a front perspective view of the funnel for the ejection port of a shotgun.

FIG. 2 is a top view of the funnel for the ejection port of a shotgun.

FIG. 3 is a bottom view of the funnel for the ejection port of a shotgun.

FIG. 4 is a left side view of the funnel for the ejection port of a shotgun.

FIG. 5 is a right side view of the funnel for the ejection port of a shotgun.

FIG. 6 is a front view of the funnel for the ejection port of a shotgun shown with the bottom side up; and,

FIG. 7 is a rear view of the funnel for the ejection port of a shotgun shown with the top side up.
